UNITED STATES PATENT OFFICE.

HARRY PICKHARDT, OF NEW YORK, N. Y., ASSIGNOR TO THE PHOENIX GLASS COMPANY, OF PITTSBURGH, PENNSYLVANIA, A CORPORATION OF WEST VIRGINIA.

DESIGN FOR A SHADE FOR ELECTRIC LIGHTS.

47,367.

Specification for Design.

Patented May 18, 1915.

Application filed February 12, 1915. Serial No. 7,884. Term of patent 7 years.

To all whom it may concern:

Be it known that I, **HARRY PICKHARDT**, a citizen of the United States, residing at New York, in the county of New York and State of New York, have invented a certain new, original, and ornamental Design for a Shade for Electric Lights, of which the following is a specification, reference being had to the accompanying drawing, forming a part thereof.

The figure is a side elevation of a shade for electric lights, showing my new design.

I claim:

The ornamental design for a shade for electric lights as shown.

HARRY PICKHARDT.

Witnesses:

E. H. LEID,

A. H. PATTERSON.
